UNITED STATES PATENT OFFICE

ALLEN M. HARRELSON, OF TROY, OHIO, ASSIGNOR TO THE HOBART MANUFACTURING COMPANY, OF TROY, OHIO, A CORPORATION OF OHIO

CENTRIFUGAL SWITCH

Application filed December 31, 1931. Serial No. 584,107.

This invention relates to centrifugal devices, and more particularly to a centrifugal switch.

It is an object of the invention to provide a centrifugally operable device adapted to serve as a switch, which is rugged, self-contained and not subject to deterioration with long use.

It is a further object of the invention to provide a self-contained centrifugal switch that is easy to install, inexpensive to manufacture, which comprises relatively few parts and which will give uniform satisfactory service over a long period of use.

Other objects and advantages of the invention will be apparent from a study of the detailed description, the accompanying drawing, and the appended claims.

In the drawing—

Fig. 1 is a broken view partially in section and partially in elevation of a centrifugal switch constructed in accordance with the present invention in place on a motor;

Fig. 2 is an end elevational view of the switch;

Fig. 3 is an end elevational view of the stationary contacts of the switch.

Fig. 4 is a plan view of a detail of the switch structure; and

Fig. 5 is a perspective view of the centrifugal switch removed from the shaft.

It is well known that single phase alternating current induction motors have no starting torque of their own. One method of starting such a motor is to provide an auxiliary or starting winding which is dephased from the main winding by an angle sufficient to produce an effective rotating electromagnetic field. After the motor

comes partly up to speed the starting winding should be disconnected to prevent its being burned out and it is therefore common practice to provide a centrifugal switch for opening the circuit to the starting winding

after the motor has come partly up to running speed. The switch of the present invention is peculiarly adapted for this use, and its construction will be described with relation to an electric motor; however, this

is to be taken as illustrative only, and not as

a limitation, for the same principles are equally applicable to other installations.

Referring to the drawing in detail, where-in there is illustrated a preferred embodiment of the invention, there is shown a motor indicated generally at 10. This motor comprises the usual field structure 11 to which is bolted by bolts 12 the end casting or bracket 13. This bracket serves to house the outer ball race 14 of a ball bearing which serves as a support for the main shaft 15 of the motor. The inner race is held in position on the motor shaft by nuts 16. A bearing cap 20 is bolted against the ball race 14 to hold the same in place by bolts 21 and is also provided with a removable plug 22 by means of which access may be had to the bearings without removing the end casting. Cover plate 24 is fastened to the bearing cap by screws 25. These parts represent any conventional motor structure and have no particular bearing upon the present invention.

The centrifugal device comprises first a carrier member 30 which is provided with an internal bore of substantially the same diameter as that of the shaft and with an extended sleeve portion 31 at one end. A shoulder 32 may be formed on the shaft 15 if desired and the sleeve 31 preferably is drawn up tightly against the same through the action of the internal ball race and nuts 16. The force of friction will be sufficiently great to rotate the sleeve without other holding means. The sleeve is also formed with a series of depressions or pockets 33 preferably radial with respect to the shaft center, separated by walls 34. A series of balls 35 are placed one in each depression and serve as rotary weights, adapted to move outwardly under the action of centrifugal force.

A disk 38 formed of insulating material is mounted upon the sleeve 31 with just enough clearance so that it does not tend to bind or to produce undue friction. The rotary contact, consisting of an annular copper strip 39, is fastened to the outer side of the disk by rivets 40. A cam plate 41 is fastened to the disk by means of screws 42 and is provided with a bent over portion 43

and guiding edge 44. A relatively large clearance is left between the edge 44 of the disk and the carrier member in order that under normal conditions there will be no contact between these two metal surfaces, thus affording a guiding means for the contact plate and cam assembly which is sufficiently yieldable to allow rotary contacts 50. A yieldable compression spring 46 is enclosed about the sleeve between the contact disk and a groove 47 which is formed in the carrier member adjacent the base of its curved portion, which spring normally tends to move the disk and the carrier member apart. The spring, carrier member, and balls are completely enclosed within and protected by the housing consisting of the disk and the cam plate. The stationary contact members comprise two spaced copper strips 50 which are connected in series with the starting winding, and which are riveted to a plate 51 of suitable insulating material. This plate is fastened to the end bracket of the motor by means of bolts or screws through holes 52. The stationary contact members are so mounted with respect to the rotational part of the switch that when the parts are standing still the spring 46 will urge the rotary contact against the fixed contact.

In the operation of the motor, assuming that the current is turned on with the motor at a standstill, the annular contact 39 is bridged across the two stationary contacts 50, and thus the circuit to the starting winding is closed. The circuit remains closed as the motor begins to turn over, and the contact disk and the cam plate are held stationary because the friction between the two metallic contact surfaces is greater than that between the disk and the rotating sleeve 31. Thus an even contact is maintained without arcing or sparking which would provoke a deterioration of the switch. As the speed of the motor increases, and when it has reached a predetermined speed, the balls 35 will fly outward by centrifugal force against the sloping face 43 of the cam plate and exert a camming action thereon. This force overcomes that of the spring 46 and therefore the contact disk and floating cam plate are quickly moved axially toward the center of the motor and the circuit to the starting winding is opened. The limited amount of frictional engagement that occurs before the final separation of the contacts assists in keeping the contacts clean. After the contacts have entirely separated, the disk and cam plate are free to rotate at the same speed as the shaft.

In slowing down after the motor has been deenergized, as soon as the point is reached where the force of the spring exceeds the centrifugal force of the balls, the

rotating contact will be forced into contact with the stationary member and will exert a limited amount of wiping action thereon until it comes to a stop. Thereafter the motor may continue to rotate for some time but during this period there is no unnecessary wear on the contacts. The switch thus keeps its contacts clean and at the same time is designed to have a maximum life without requiring replacement of parts.

It will be noted that the centrifugal device is enclosed, and is thus effectively protected against dirt or any foreign material which might happen to get into the interior of the switch and prevent its proper operation. This feature is of importance in many motor installations where the motor must operate in an atmosphere which is filled with particles of dirt or dust. It will also be noted that this device is a unitary structure which can be slipped onto the shaft of the motor in a single operation. It may be held in place as illustrated and previously described, or by a set screw in carrier member 30 bearing against the shaft.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A centrifugal starting switch for a single phase motor comprising a carrier member rotatable with the shaft of said motor and formed with a series of radial depressions, balls in said depressions adapted to roll outwardly under centrifugal force, a cam plate and contact carrying disk assembly floating on said shaft, said cam plate adapted to cooperate with said balls, a fixed contact, and a spring enclosed within said cam plate and disk and normally urging said contacts together.

2. A centrifugal switch comprising a rotary shaft, a disk of insulating material, a cam plate fastened to said disk and floating on said shaft, said disk and said plate forming a housing, centrifugal means within said housing cooperating with the cam member to move said member in one direction in response to a predetermined speed of rotation of said shaft, yieldable means within said housing tending to cause movement of said member in an opposite direction, and a contact carried by said disk.

3. A centrifugal switch comprising a rotating shaft, a carrier member fixed to said shaft, a plurality of radially movable weights rotated by said member, a contact disk loosely mounted on said member, a fixed contact, a cam plate attached to said disk and having a face cooperating with said

weights, yieldable means urging said contacts toward closed position, said weights movable outwardly by centrifugal force against said plate to cause the separation of 5 the contacts.

4. A self-contained centrifugal device adapted to be readily attached to a rotating shaft comprising a carrier member rotatable with the shaft, a plurality of pockets formed 10 in said member, a plurality of weights carried in said pockets, a disk floating on said member and adapted to move axially and rotationally thereon, a cam plate carried by said disk, yieldable means tending to move 15 said disk and plate in one direction, said weights and said plate cooperating to move said disk and plate in another direction, said disk and plate serving to completely enclose said pockets, said weights, and said yieldable 20 means.

5. A centrifugal device comprising a carrier member, a floating disk mounted on said member, a cam plate carried by said disk, means tending to move said disk in one 25 direction, centrifugally operable means cooperating with said plate for moving said disk in the opposite direction, both said means being enclosed by said disk and said plate.

6. A centrifugal starting device for a motor adapted to be placed on the shaft of the motor as a unit comprising a carrier member formed with an extended sleeve, a disk of insulating material floating on said sleeve, 35 a cam plate mounted on said disk, weights rotatable with said carrier and cooperating with the cam plate, and yieldable means urging the cam plate and said carrier part, said weights at a predetermined speed of rotation 40 adapted to move outwardly by centrifugal force to cause the disk and carrier to move relatively toward each other.

7. A centrifugal switch comprising a rotary shaft, a carrier member rotatable with 45 the shaft, a plurality of weights carried by said carrier member, a disk of insulating material mounted on said shaft, a contact carried by said disk, an imperforate plate fastened to said disk and extending over 50 said carrier member to form a dirt proof housing enclosing said member and said weights, a fixed contact, and yieldable means urging said contacts together, said weights under the action of centrifugal force adapt- 55 ed to cooperate with said plate to separate said contacts.

8. A starting switch for a single phase motor comprising a rotary shaft, a carrier member rotatable with the shaft, centrifu- 60 gally operable weights carried by said carrier member, a disk of insulating material floating on said shaft, a contact carried by said disk, a plate fastened to said disk, a fixed contact, and yieldable means for urg- 65 ing said contacts into circuit closing position,

said disk and plate forming a dirt proof housing enclosing said weights and said yieldable means.

9. A centrifugal switch comprising a rotary shaft, a carrier member formed with an extended sleeve and rotatable with the shaft, centrifugally operable weights carried by 70 said carrier member, a disk of insulating material mounted on said sleeve, a contact carried by said disk, an imperforate plate fastened to said disk and terminating closely adjacent said carrier member, said plate and said disk forming a dirt proof housing enclosing 75 said carrier member and said weights, a fixed contact, and yieldable means for urging said contacts together.

10. A starting switch for a single phase motor having a shaft comprising spaced stationary contacts mounted on the end bracket of the motor and connected in the starting 80 winding circuit, a carrier member slidable onto the shaft and rotatable therewith, a plurality of radially extending pockets formed in said member, weights in said pockets, an insulating disk floating on said 85 member, a contact ring on said disk, a cam plate carried by said disk cooperating with said weights, and yieldable means normally urging said ring and said contacts together 90 to close the starting winding circuit, said weights adapted to move outwardly by centrifugal force to cause the separation of said ring from said contacts.

In testimony whereof I hereto affix my signature.
